FASTENER-INSERTING MECHANISM

Alphonse C. Kulik, Ipswich, Mass., assignor to
 United Shoe Machinery Corporation, Flemington, N. J., a corporation of New Jersey

Application June 11, 1949, Serial No. 98,547

8 Claims. (Cl. 1—20)

1

This invention relates to machines for inserting fasteners, and particularly to improvements in fastener-inserting mechanism of the type disclosed in United States Letters Patent No. 2,415,410, granted February 11, 1947, on an application filed in the name of Benjamin B. Blanchard, and which is therein illustrated as applied to a lasting machine of the kind shown in United States Letters Patent No. 1,815,295, granted July 21, 1931, on an application filed in the name of George Goddu. It will be understood, however, that features of this invention are not limited to use in fastener-inserting mechanism or lasting machines of the exact mechanical construction shown in the aforementioned patents.

In the fastener-inserting mechanism disclosed in the Blanchard patent, the fastener, consisting of a staple formed from a piece of wire, is driven through the overlaid marginal portion of a shoe upper and into a sole member by means of a driver and, as the staple is thus driven, its legs are progressively curved, or bent, within the substance of the work by means of a staple deflector which had been caused to enter the work prior to the insertion of the staple. After the staple has been driven and before the fastener-inserting mechanism is moved away from a position in engagement with the overlaid marginal portion of the upper, which has just been secured to the sole member, the staple deflector is withdrawn from the work. As is explained in the Blanchard patent, the driver and deflector are operated in time relation from a common actuating member and by means of mechanism including a latch which, at the proper point in the operating cycle, is tripped from engagement with a latch plate to permit the intermediate withdrawal of the deflector through the action of a spring. While the aforementioned mechanism operates in a satisfactory manner to effect entry and withdrawal of the deflector, as above described, it has sometimes been found that there is a slight tendency for the deflector to bounce, or vibrate, once or twice, because of the impact of the latch on the latch plate. When such action occurs, a considerable portion of the energy which would otherwise be utilized to effect insertion of the deflector into the work is dissipated, with the result that, instead of penetrating the overlaid upper materials, the deflector may displace the shoe downwardly. Now, when the driver is operated, the staple will be driven above the work and its crossbar will not be embedded in the upper material. Also, dur-

ing such bouncing of the deflector, the latch may be accidentally disengaged with the result that the deflector is withdrawn before the staple is driven and the legs of the staple are not curved by the deflector.

It is an object of this invention to provide improved mechanism for operating the deflector of a fastener-inserting machine of the above type which is characterized by a more definite and positive control over the movements of the deflector when the same is being caused to enter the work. For the accomplishment of this purpose, in the herein illustrated fastener-inserting mechanism the deflector is operated, from the common actuating member, by means of mechanism including members arranged to form a toggle which, when straightened, provides a positive drive connection for effecting movement of the deflector into the work and, when broken, will permit withdrawal of the deflector by means of a spring. Conveniently, the toggle may be broken by means that is actuated by the common actuating member in generally the same manner as in the aforementioned Blanchard patent.

Another object of this invention is to provide improved means for supporting and adjusting the deflector so that it may be shifted, relatively to the driver, to vary the curvature of the staple legs. Preferably, and in the herein illustrated machine, adjusting movements of the deflector take place along a rectilinear path which is perpendicular to the operating surfaces of the deflector. With this arrangement, adjustment of the deflector toward or away from the driver, for the purpose of changing the curvature of the staple legs, may be effected without altering the angular relationship between the deflector and the bottom of the shoe. Also, the improved means for supporting and adjusting the deflector is adapted to facilitate the removal and installation of the deflector.

With the above and other objects and features in view, the invention will now be described in connection with the following detailed description of a preferred embodiment thereof, illustrated in the accompanying drawings, and will be pointed out in the claims.

In the drawings,

Fig. 1 is a view in side elevation of a portion of a machine embodying the features of this invention;

Fig. 2 is a view similar to that of Fig. 1 but showing the operating elements in different positions;

Figs. 3 and 4 are views in perspective of one

of the component mechanisms of the machine shown in Fig. 1 with certain parts broken away, or omitted, and others shown in section, and

Fig. 5 is a view in side elevation of one of the parts of the machine.

Referring to the drawings, the lasting machine and fastener-inserting mechanism therein illustrated are, with the exceptions to be noted below, similar to those shown respectively in the aforementioned patents. Hence, the lasting machine comprises a gripper, having jaws 10, 10 for tensioning the upper A of a shoe over a last B, carrying a sole member C, and an overlaying member forming part of a fastener-inserting mechanism for laying the lasting margin of the upper in over, and for securing it to, the sole member by means of staples D. These elements operate in the same general manner as the corresponding parts of the machine disclosed in the Goddu patent and the usual edge gage 12 and shoe-bottom rest 14 are provided.

As in the machine of the Blanchard patent, the upper-fastening mechanism, including means for forming staples above the line of drive and for transferring them into alignment with the staple driver, is for the most part movable bodily toward and from the work piece in directions inclined to the bottom face of the sole member C and the movement toward the work piece is utilized to lay the marginal portion of the upper inwardly over the insole into position to be fastened. Secured to the head of the machine is a supporting member 16 (Figs. 1 and 2) provided with a forwardly and downwardly inclined guideway for a slide 18, this slide having mounted thereon the staple transferring, driving and deflecting mechanisms and a portion of the staple forming mechanism. For moving the slide 18 along its guideway toward and from the work piece, the slide carries a cam roll 20 engaging a cam groove in a cam disk (not shown) mounted on a cam shaft (not shown) of the machine.

The staple is formed from a piece of wire (which is the front end portion of a wire strand) after this piece of wire has been fed into the staple forming mechanism by wire feeding mechanism (not shown), and severed from the wire strand by wire severing mechanism (not shown). The wire severing, staple forming and staple transferring mechanisms with which the present machine is provided are the same as the corresponding mechanisms of the machine disclosed in the above mentioned Goddu patent. These mechanisms in part are mounted on a bracket 22 (Figs. 1 and 2) integral with the front portion of the supporting member 16 and in part are carried by a member 27 mounted on a bracket 24 secured to the lower front end portion of the slide 18 by screws 26. The wire is advanced by the wire feeding mechanism through a flexible conduit 28 (Fig. 2) to a wire nozzle comprising blocks 30 secured by a screw 32 on an upwardly extending part of the member 27. The wire is fed through an outside staple former (not shown) supported on the bracket 22 on which is also provided a severing knife (not shown). After the wire has been fed through the outside staple former, the slide 18 is caused to move downwardly and forwardly in the machine toward the shoe presented to the machine with the result that the front end portion of the wire strand is severed. An inside staple former (not shown) mounted on the member 27 engages, as a result of the forward movement of the slide 18, the severed piece of wire and pushes

it into the outside former to form a staple. Thereafter, the staple transferring mechanism becomes active to move the formed staple into staple driving position. The staple is moved by a transferring member 34 (Fig. 1) which is mounted for movement heightwise of the machine in the slide 18 and which is actuated by a cam operated bar 36. The staple when moved into driving position is tilted by the transferring member 34 and lowered into a throat which, in construction and function, is like the throat or nozzle of the machine of the above-mentioned Goddu patent. The throat comprises plates 38 (Figs. 1 and 2) secured in opposed relation by screws 40 to plates 42. The plates 42 are provided at their upper ends with flanges 46 which are fastened by screws 48 to the member 27 on the slide 18. The plates 38 are shaped to extend inwardly under the lower edges of the plates 42 and to provide a guideway for a staple driver, to be described, which is T-shaped in cross section.

The staple driving mechanism comprises a driver 56 (Figs. 1 and 2), already mentioned, which is reciprocated in the guideway formed by the plates 38 by mechanism to be described. The driver 56 extends into and is movable with relation to a casing 58 (Figs. 1 and 2) that contains a driver clamping mechanism and a part of the driver actuating mechanism. The casing 58 is secured by screw bolts 60 to a forward extension 62 of the slide 18, the casing 58 and driver thus participating in the movements of the slide 18. The lower end of the casing 58 is provided with a rearward extension 64 engaging a notch provided in the plates 38 and 42 to give additional support to the casing 58. Moreover, the extension 64 has parallel flanges 66 engaging the outsides of the plates 42. The driver 56 extends into a substantially rectangular block 68 which has a sliding fit in the casing 58 and is provided with a bore shaped to accommodate the driver (Fig. 1). The block 68 is recessed to admit a clamping screw 70 which serves to secure the driver 56 to the block 68. The block 68 is also provided with cylindrical recesses forming a socket in which is received a cylindrical block 72 having a heightwise extending groove which is engaged by the lower end of a small arm 74 extending through an aperture into the casing 58 and being adjustably secured to a driver operating lever 76. The driver 56 thus is fulcrumed on the arm 74. The driver operating lever 76 is rotatably mounted on a shaft 78 (Figs. 1 and 2) extending through the forward extension 62 of the slide 18 and secured against rotation. More specifically, the driver operating lever 76 is mounted on a sleeve 80 on the shaft 78.

To rock the driver operating lever 76 about the shaft 78, thereby to reciprocate the driver 56, there is provided an operating member in the form of a bell crank lever 92 fulcrumed on a shaft 94 mounted in the slide 18. The bell crank lever 92 has a forwardly extending arm carrying a cam roll 96 which engages a cam track 98 provided in the driver operating lever 76. Downward movement of the cam roll 96 in the cam track 98 causes a swinging movement of the lever 76 in a counterclockwise direction as viewed in Fig. 1, as a result of which the driver 56 is retracted. On the other hand, upward movement of the cam roll 96 causes a rotation of the lever 76 in a clockwise direction, as a result of which the driver 56 is moved toward the shoe to insert a staple therein. The cam track 98 is so shaped that at the beginning of the upward movement of the roll 96

therein there is a short dwell in the movement of the lever 76, for a purpose to be described. The bell crank lever 92 is spring operated to impart to the driver 56 its driving stroke. To this end there is mounted on the hub portion 102 of the bell crank lever 92 a torsion spring 102 one end of which engages a lug 104 on a downwardly extending arm 106 of the bell crank lever 92 and the other end of which engages a portion of the slide 18.

As in the machine of the above mentioned Goddu patent the slide 18, after having moved downwardly and forwardly and after the driver has been operated, is retracted with the driver in its lowermost position. During the retraction the downwardly extending arm 106 of the bell crank lever 92 is caused to become locked. To this end the arm 106 is provided with a latch plate 108 which is engaged by a latch 110 pivotally secured on a cam operated lever 112 rotatably mounted on the machine frame, the latch 110 being biased by a spring 114 which tends to swing the latch 110 about its pivot into latching position. After the latch 110 has engaged the latch plate 108 and when the slide is again advanced downwardly toward the shoe bottom, the bell crank lever 92 due to its latching engagement with the lever 112, is rotated in a clockwise direction (Fig. 1), thereby partially loading the spring 102.

After the slide 18 has arrived in its forward operative position a trip screw 116, secured in a lug of the slide 18, has been moved into the immediate vicinity of an upwardly extending arm 118 of the latch 110. However, the latch 110 is not tripped to free the bell crank lever 92 by the screw 116 pushing against the arm 118 of the latch 110 but rather the lever 112 which carries the latch 110 is operated by its cam (not shown) to complete the loading of spring 102 and to cause the arm 118 to abut the screw 116, thereby tripping the latch 110 and releasing the bell crank lever 92 to the force of its spring 102. The reason for this arrangement is to time the operation of the driver 56 to occur somewhat after the slide 18 has arrived in its operative position. Rotation of the bell crank lever 92 in a clockwise direction, as viewed in Fig. 1, thereby loading the spring 102, as above described, results in a downward movement of the cam roll 96 in the cam track 98 in the cam lever 76 so that the driver 56 is withdrawn. Tripping the latch 110 causes a quick upward movement of the cam roll 96 as a result of which the driver 56 is propelled downward to drive the staple into the work with the bar of the staple parallel to the sole edge.

To cause the staple, when being driven, to follow a curved path in the work so that the staple curls back toward the surface of the sole member C whence it was driven, without penetrating the entire thickness of the sole member, the staple legs are progressively bent or deflected during the driving operation. To this end there is provided a deflector 120 (Figs. 1-5) comprising a bifurcated awl-like member which is arranged to enter the work, that is to say to pierce the overlasted marginal portion of the upper and to penetrate part way into the sole member C, as illustrated in Fig. 2 of the drawings. The deflector 120 is caused to enter the work at a point opposite the outlet end of the throat where the staple emerges when being driven by the driver 56. The two prongs 122 of the deflector 120 have cylindrically shaped grooves 123, as illustrated best in Figs. 3 and 4, which are engaged by the staple legs after the latter have entered the work. The grooves serve to curve or

bend the staple legs laterally of the crossbar of the staple so as to make the staple curl away from the edge of the sole member C and back toward the surface of the work whence the staple entered (see Fig. 2). In the herein illustrated machine, the deflector 120 is mounted to move heightwise of the machine into and out of engagement with the work in a direction that is inclined to the work surface, whereas the driver 56 moves in a direction inclined at an acute angle toward and from the work surface, the driver when on its operative stroke moving inwardly of the machine and outwardly of the bottom of the shoe toward the adjacent edge of the sole member and the deflector moving outwardly of the machine and inwardly of the shoe bottom. Moreover, the deflector 120, as will be described, also is mounted to move with the slide 18.

Turning now to the improved means for supporting and adjusting the deflector, the two prongs 122 of the deflector are formed integrally with a pair of guide flanges 124, 124 and a cylindrical stem 126. This stem is slidably supported in a bore 130 formed in a deflector-carrying block, or guiding member, 132, Figs. 3 and 4. The block 132 has a pair of flanges 134, 134 which fit in grooves 147, 147, formed in portions of the bracket 148, and a pair of downwardly extending ribs 133, 133, which are engaged by the guide flanges 124, 124 on the deflector stem 126. As will be apparent, the ribs 133 and guide flanges 124 provide a very positive means for supporting the deflector against the thrust of the staple, when the staple is driven, and also prevent any tendency for the deflector to rotate. Also, the deflector-carrying block 132 is very firmly supported on the long bearing surfaces provided by the flanges 134.

The bracket 148 is secured to the bracket 24 for adjustment in two directions at right angles in the following manner. The member 27, which, as explained above, carries parts of the staple-forming and transferring mechanisms, is provided with grooves 153, 153 which extend at right angles to each other and the brackets 24 and 148 have tongues 155 that fit into these grooves, Fig. 3. Screws 149 pass through oversized holes 151, formed in the bracket 24 and the member 27, and are threaded into the bracket 148, Fig. 1, while a single screw 149a passes through a similar clearance hole in the bracket 24 and is threaded into the member 27. As will be pointed out below, this arrangement permits independent adjustment of the member 27 and the bracket 148. Referring particularly to Figs. 1 and 2, it will be seen that the deflector is mounted for movement toward and away from the work in a path that is inclined downwardly and outwardly of the machine. Hence, when the deflector is caused to enter the work, e. g., the lasting margin of the upper material A, it will have a tendency to urge the lasting margin inwardly over the sole member thus additionally tensioning the upper materials.

On a rearwardly extending part of the block 132 there is a pin 142 which enters a slot 144, cut in an arm 143, Fig. 4. This arm is pinned to one end of a shaft 146, journaled in the bracket 148. Secured to the opposite end of this shaft is a handle 150 which carries a spring-pressed detent 152, Figs. 4 and 5. The slot 144 is eccentric to the axis of the shaft 146 so that when this shaft is rotated by the handle 150 the block 132 will be shifted, and the deflector adjusted, back or forth in the bracket 148 along a rectilinear path defined by the grooves 147, see arrow Fig. 4. However, when the deflector is thus adjusted, neither

the direction of movement of the deflector, relatively to the shoe bottom, when it is inserted in the work, or the angular relationship between the grooves 123, 123 in the deflector and the direction of movement of the driver 56 will be altered. Hence, the curvature of the staple legs may be varied without disturbing the action of the deflector in any respect. For holding the handle 158 in different positions, it is provided with a detent 152 adapted to engage either a notch 153, formed in a quadrant arm 156, or a stop 154, adjustably secured to the quadrant arm. As will be apparent from Fig. 4, which is an exploded view, and Fig. 5, when the parts are assembled this quadrant arm is secured to the bracket 148 by means of a screw 151.

The improved mechanism for moving the deflector 120 in a heightwise direction and at an angle to the bottom face of the sole member C, into and out of the work, will now be described. Snugly fitted in a bore in the upper end of the stem 126 of the deflector is a pin 168 which is provided with a slotted head 167 and two flat surfaces 169, 169, Figs. 3 and 4. The block 132 is slabbed off at its upper end and is embraced by the bifurcated end of an arm 172, a portion 173 of which is provided with a slot 170 adapted to fit over the flattened surfaces 169, 169 on the pin 168. One end of this slot is enlarged at 171 to a size somewhat bigger than the pin 168 for the following purpose. The eccentric slot 144 is provided with an axially extending portion 145, Fig. 4. When the shaft 146 is rotated to a position where the pin 142 is in line with this portion of slot 144, the block 132 may be slid to the left, Fig. 3, until pin 168 is in line with the enlarged portion 171 of slot 170. Now the pin 168 may be withdrawn and the deflector removed. The arm 172 is rotatably mounted on a shaft 174, journaled in the bracket 143, and outside of this bracket, a second arm 178, secured to the arm 172 by means of a web 175, is also journaled on this shaft. When the arm 178 is oscillated, the deflector 120 will be moved up and down in a manner that will be apparent from looking at Figs. 1 and 2.

For thus oscillating the arm 178, the following mechanism is provided. A link 179 connects the arm 178 to the lower end of another arm 180 which is journaled on the shaft 178, Figs. 1 and 2. Also journaled on this shaft is a deflector-operating lever 184. A coil spring 182, which engages a pin 183 on the arm 180 and a pin 185 on the lever 184, biases the arm 180 in a clockwise direction around the axis of shaft 178 and so as to elevate the deflector. The operating lever 184 is formed with a cam track 186 which is engaged by a cam roll 188 carried by the bell-crank lever 92 and rotatable on the same axis as that of cam roll 96. The lever 184 is connected to the arm 180 in the following manner. A pair of toggle links 190 and 192 are connected together by a pin 191 and are pivoted respectively to the arm 180 and the lever 184 by means of pins 193 and 195. The link 192 extends upwardly beyond the lever 184 at 197 and this extension carries a pin 199 which is embraced by the end of an arm 196 forming part of a bell-crank lever 200. The bell-crank lever 200 is pivoted on a portion of the lever 184 by means of a pin 201, and a tail portion of this lever is in line with an extension 204 of the cam roll 188, a stop pin 203 being provided to limit movement of the bell-crank lever 200. A coil spring 206 is wrapped around the pin 195 and arranged to bear on the lever 184 and the

link 192 in such a manner as to tend to straighten the toggle formed by the links 190 and 192, and an adjustable stop screw 208 is threaded into a portion of the slide 18 in a position to be engaged by an extension 181 of the arm 180.

The operation of the herein illustrated machine to sever a length of wire, form it into a staple, transfer the staple down into alinement with the driver, and drive the staple, is the same as that of the machine disclosed in the Goddu patent, as is also the action of the gripper jaws 10, 10 to seize the upper, pull it heightwise of the last, and draw it inwardly over the sole member, and will not be described. However, as will be pointed out below, the gripper jaws are moved inwardly over the shoe bottom by the throat member, instead of by a spring as in the Goddu patent. Likewise, the overall action of the mechanism for operating the driver and the deflector, in proper time relation, is similar to that described in detail in the Blanchard patent and need not be repeated. However, with the improved deflector-operating mechanism described above, a somewhat different action is obtained. Referring to Figs. 1 and 2, the latter shows the positions of the various parts after the deflector has been caused to enter the work and just after the staple has been driven. When being rotated, in a counterclockwise direction by spring 102 and to the position shown in Fig. 1, the lever 92 first effects angular movement of the deflector-operating lever 184 (cam roll 188 and cam track 186) in a counterclockwise direction, and inasmuch as the toggle formed by the links 190, 192 is at this time straightened, the arm 180 is swung in the direction to effect movement of the deflector 120, through the link 179 and arms 178 and 172, downwardly and into the work. Next, the driver arm 76 is actuated (cam roll 96 and cam track 98) to effect operation of the driver to drive the staple, the cam track 98 being shaped so as to delay such action of the driver until after the deflector has been operated, and the parts eventually reach the positions shown in Fig. 2.

Upon a slight additional movement of the lever 92, the extension 204 on the cam roll 188 strikes the bell-crank lever 200 and rotates it in a direction to swing the link 190 in a clockwise direction, thus breaking the toggle formed by links 190, 192 and permitting the spring 182 to move the arm 180 in a direction to effect withdrawal of the deflector from the work, Fig. 1, such movement of the arm 180 being limited by the engagement of extension 181 with the stop screw 208. During such additional movement of the lever 92, the cam rolls 96 and 188 travel along dwell portions in cams 98 and 186 so that no movement of the driver or deflector occurs. The slide 18 is now withdrawn to complete the operating cycle. When the slide 18 is again moved forwardly, to the right, Figs. 1 and 2, latch 110 catches the plate 108 and causes the member 92 to be rotated in a clockwise direction and the spring 102 to be cocked partially, as above explained. As the member 92 is thus rotated reversely, the driver 56 is retracted and the deflector-operating lever 184 swung in a clockwise direction. The extension 204 on the cam roll 188 now moves away from the bell-crank lever 200 and, since the arm 180 is held against rotation in this direction by the stop 208, the toggle formed by the links 190 and 192 will be straightened, assisted by the action of the spring 206, thus re-

storing the parts for the next operation of the deflector.

With the foregoing arrangement, motion of the lever 184 is transmitted to the arm 180, and thus to the deflector 120, by means of the toggle 190, 192. Inasmuch as this toggle provides a positive drive connection, it is impossible for the deflector to bounce, or vibrate, as it is being operated. Accordingly, the deflector will certainly be inserted into the work and the work held in the proper position relatively to the driver and deflector when the staple is driven, thus assuring that the legs of the staple will be properly curved within, and the crossbar of the staple embedded in, the work. However, upon the breaking of the toggle, in the manner described above, the deflector will be immediately withdrawn by means of the spring 182.

Referring again to the improved deflector supporting and adjusting mechanism shown particularly in Figs. 3 and 4, the relatively long bearing surfaces afforded by the flanges 131 and grooves 147, provide a very rigid and unyielding support for the deflector-carrying block 132 while, at the same time, permitting movement of this block for adjusting the position of the deflector to vary the curvature of the staple legs by means of the hand lever 150. As has been already suggested above, such adjusting movements of the block 132 are effected along a rectilinear path at right angles to the operating surfaces of the deflector so that neither the angular relationship between the deflector and the driver nor between the deflector and the work is disturbed. Also, if it should become necessary to replace a deflector for any reason, removal of the old deflector and installation of a new one can be effected readily in a few moments, and without the need for any special tools, by merely moving the handle 150 to a position in which pin 162 is in line with the axially extending portion 145 of slot 144. The block 132 may then be moved back to a position where pin 168 can be removed through hole 171.

When the machine is first assembled, or at any later time, the member 27 and the bracket 148 may be very readily adjusted for the purposes of lining up the staple-transferring mechanism with the driver and of positioning the deflector so as to line up its grooves with the legs of the staple, in the following manner. First, the screw 149a is partially tightened, the member 27 shifted back and forth until the transfer mechanism is in proper position, and finally the screw 149 is fully tightened. Now the same procedure may be followed with the screws 149 and the bracket 148 without, however, disturbing the previously made adjustment of the member 27. As suggested above, the deflector is arranged to move in a path that is inclined downwardly and outwardly of the machine and this arrangement is provided for the following reason. After the upper materials have been tensioned and drawn inwardly over the sole member, the deflector is caused to enter the lasting margin and, since the direction of movement of the deflector is inclined to the sole member, the deflector, in penetrating the upper materials, tends to impart a slight additional inward movement to the lasting margin, thus further tensioning the upper materials. With the deflector thus mounted for movement along a path which is inclined to the work, the driver casing 58 may be arranged in the location shown in Figs. 1 and 2 and at a

rather steep angle to the work. Such location of the driver casing affords a sufficient space, between the casing and the work, to receive the gripper jaws 10, 10 with these jaws directly in line with the deflector 120 and the throat, formed by plates 38, 38. With the gripper jaws so located, lasting of a shoe may proceed in either direction relatively to these elements. Also, the movement of the gripper jaws in a direction to draw the lasting margin of the upper materials A inwardly over the sole member C may now be conveniently effected by the action of the throat member which will push the jaws in this direction as it is moved to the position shown in Figs. 1 and 2. Hence, the usual overdraw spring, provided in the machine shown in the Goddu patent, may be omitted if desired.

Having described the invention, what I claim as new and desire to secure by Letters Patent of the United States is:

1. A fastener-inserting mechanism having, in combination, a work-entering deflector and a staple driver, driver-operating means and deflector-operating means, and positive drive connections between said driver-operating means and the deflector-operating means including a pair of members forming a toggle, said toggle being operative, when straightened, to cause the deflector to enter the work on actuation of the driver-operating means.

2. A fastener-inserting mechanism having, in combination, a work-entering staple deflector and a staple driver, driver-operating means and deflector-operating means, positive drive connections between said driver-operating means and the deflector-operating means including a pair of members forming a toggle, said toggle being operative, when straightened, to cause the deflector to enter the work on actuation of the driver-operating means, means tending to withdraw the deflector from the work, and automatically controlled means for breaking the toggle immediately after the driving of a staple to permit the deflector to be withdrawn from the work by said last-mentioned means.

3. A fastener-inserting mechanism having, in combination, a work-entering staple deflector and a staple driver, driver-operating means and deflector-operating means, positive drive connections between said driver-operating means and the deflector-operating means including members forming a toggle, said toggle being operative, when straightened, to cause the deflector to enter the work on actuation of the driver-operating means, yielding means tending to straighten the toggle, spring means tending to withdraw the deflector from the work, and means controlled by the driver-operating means for breaking the toggle immediately after the driving of a staple to permit said spring means to withdraw the deflector from the work.

4. A fastener-inserting mechanism having, in combination, a work-entering staple deflector and a staple driver, driver-operating means and deflector-operating means, positive drive connections between said driver-operating means and the deflector-operating means including a pair of links forming a toggle, said toggle being operative, when straightened, to cause the deflector to enter the work on actuation of the driver-operating means, yielding means tending to straighten the toggle, spring means tending to withdraw the deflector from the work, and means controlled by the driver-operating means for breaking the toggle immediately after the driving of a

staple to permit said spring means to withdraw the deflector from the work.

5. A fastener-inserting mechanism having, in combination, a deflector adapted to enter the work and to curve a fastening progressively in the driving operation and a fastening-inserting driver, a slide for supporting the deflector and the driver in operative relation, a deflector-guiding member in which said deflector is mounted for movement toward and away from an operative position within the work, and means associated with said slide for supporting said deflector-guiding member for movement along a rectilinear path, relatively to said driver, for varying the curvature imparted to the fastening by the deflector.

6. A fastener-inserting mechanism having, in combination, a deflector adapted to enter the work and curve a fastening progressively in the driving operation and a fastening-inserting driver, a slide for supporting the deflector and the driver in operative relation, a deflector-guiding member in which said deflector is mounted for movement toward and away from an operative position within the work, and means associated with said slide for supporting said deflector-guiding member for movement along a rectilinear path, relatively to said driver, for varying the curvature imparted to the fastening by the deflector.

7. A fastener-inserting mechanism having, in combination, a deflector adapted to enter the

10
15

work and to curve a fastening progressively in the driving operation and a fastening-inserting driver, a slide for supporting the deflector and driver in operative relation, a deflector-guiding member in which said deflector is mounted for movement toward and away from an operative position within the work, means associated with said slide for supporting said deflector-guiding member for movement along a rectilinear path, relatively to said driver, for varying the curvature imparted to the fastening by the deflector, and means for effecting such movements of the deflector-guiding member along said path.

8. A fastener-inserting mechanism having, in combination, a deflector adapted to enter the work and to curve a fastening progressively in the driving operation and a fastening-inserting driver, a slide for supporting the deflector and driver in operative relation, a deflector-guiding member in which said deflector is mounted for movement toward and away from an operative position within the work, means associated with said slide and formed with guideways for supporting said deflector-guiding member for movement along a rectilinear path, relatively to said driver, for varying the curvature imparted to the fastening by the deflector, and means for effecting such movements of the deflector-guiding member along said path.
